UNITED STATES PATENT OFFICE.

HAMILTON E. SMITH, OF NEW YORK, N. Y.

REVERSING BELT-GEAR.

SPECIFICATION forming part of Letters Patent No. 408,049, dated July 30, 1889.

Application filed September 29, 1887. Serial No. 261,039. (No model.)

To all whom it may concern:

Be it known that I, HAMILTON E. SMITH, a citizen of the United States, residing at New York, in the county and State of New York, 5 have invented new and useful Improvements in Reversing Belt-Gears, of which the following is a specification.

This invention relates to devices for imparting reverse motions to a shaft by means 10 of belts; and it consists in certain improvements on the device described in United States Patent No. 355,569, whereby the same can be used to actuate the driving-shafts of any number of machines. The novel mechanism 15 whereby this result is accomplished is fully pointed out in the following specification and claims and illustrated in the accompanying drawings, in which—

Figure 1 represents a perspective view of 20 the reversing belt-gear as applied to use. Fig. 2 is a sectional plan or top view of the same on a larger scale than the preceding figure. Fig. 3 is a vertical section in the plane $\alpha \alpha$, Fig. 2. Fig. 4 is a transverse section in the 25 plane $\gamma \gamma$, Fig. 2.

Similar letters indicate corresponding parts.

In the example shown in the drawings I have shown my reversing belt-gear as actuating 30 a number of cylindrical washing-machines of a well-known type; but it is obvious that it may be applied to actuate a number of any other machines where a reverse rotary movement is required.

In the drawings, the letter A designates a 35 main shaft, and B is a counter-shaft, both supported by suitable hangers, as usual. The pulleys C on the driving-shafts of the machines C, Fig. 1, are connected by belts C' with the pulleys C' on the counter-shaft B, in 40 the usual manner. A reversing rotary motion imparted to the counter-shaft B is transmitted to the driving-shafts of all the machines C.

On the counter-shaft B are arranged side 45 by side three pulleys D, E, and F, all having the same diameter and width of face. The outer pulleys D and F are mounted loosely on the shaft, while the central pulley E is rigidly secured thereto. Two belts G and H 50 connect these pulleys with a wide driving-pulley I on the main shaft A, the belt G being an open one and the belt H a crossed one. It

being assumed that the main shaft A rotates continuously in the direction of arrow 1, Fig. 3, the counter-shaft B is rotated in the direction of arrow 2, Fig. 3, when the open belt G is on the fast pulley E, and in the opposite direction when the crossed belt H is on said pulley. On inspection of Fig. 4 it will be observed that when one of the belts is on the 60 fast pulley E the other belt is on a loose pulley.

To shift the belts G and H automatically on and off the fast pulley, I make use of a shifting mechanism, which is actuated from 65 the main shaft A or other source of power, which is independent of the counter-shaft B, the pulleys D E F, and the belts G H. In this respect my present reversing belt-gear differs from that described in my patent previously alluded to, as in that patent the shifting mechanism is actuated from one of the pulleys D E F, and hence by the belts G H. This shifting mechanism consists of a cam J 70 made in the shape of a drum, (Fig. 2 especially,) to which a rotary motion in one direction can be imparted from the main shaft A, as will be presently explained.

The cam is loosely mounted on a shaft K, having bearings in pendent brackets K'. In 80 said cam are formed two cam-grooves L and M, Fig. 2, which actuate the shifting mechanism for the belts G and H. The belt-shifter for the open belt G consists of a slide n, having bearings in a box k, extending from 85 one of the brackets K' and in a hanger k'. From the slide extends downwardly, Fig. 3, an arm n', which carries a roller-stud n², that projects into the cam-groove M. A second arm n³ extends upwardly and is provided 90 with an eye through which the open belt G passes. The belt-shifter for the crossed belt H is constructed similarly to the shifter for the open belt, it consisting of a slide o, arranged parallel with the slide n and having 95 common bearings therewith, an upwardly-extending arm o', carrying a roller-stud o², that projects into the cam-groove L, and a second arm o³, extending downwardly and provided with an eye through which the crossed belt 100 H passes. The roller-studs n² and o² of the two belt-shifters engage with the cam-grooves L and M from opposite sides of the cam J. The cam-grooves are similar to each other,

but are so arranged that first one belt-shifter is actuated and then the other—that is to say, the belt which is on the tight pulley E is shifted upon a loose pulley before the belt on the loose pulley is moved at all, whereby adverse forces do not act on the tight pulley at the same time.

The cam-grooves are so timed that after the shifting of the belt from the tight pulley to a loose pulley a short interval of time elapses before the second belt is moved toward the tight pulley. During this interval the momentum of the tight pulley and counter-shaft is partially or totally expended, and when the second belt is shifted on the tight pulley no shock is caused as a reversal of the rotation takes place. The cam J is rotated slowly in order to allow the counter-shaft to make ten or twelve revolutions before the belts are shifted. Provisions are also made for throwing the cam out of gear and for changing its speed of rotation.

The rotary motion of the main shaft A is transmitted to the cam J by a speed-wheel P, Figs. 1, 2, and 3, that is loosely mounted on the shaft K of the cam, and is connected by a belt *p* with a speed-wheel P', mounted on the main shaft A. A clutch R, Fig. 2, keyed to the shaft K and movable in the direction of the length thereof, normally engages with the hub of the speed-wheel P, whereby the shaft is caused to revolve. From the shaft a slow rotary motion is imparted to the cam J through a small gear *s*, which meshes into a large gear S, mounted rigidly on one end of a spindle *t*, on the opposite end of which is a small gear *s'*, which engages a large gear S', attached to the cam. During the time that both belts G and H are respectively on the loose and fast pulley D and F the clutch R may be disengaged from the hub of the speed-wheel P, thereby disengaging the cam J, in consequence of which the belt-shifters remain

idle and the counter-shaft B ceases to revolve.

What I claim as new, and desire to secure by Letters Patent, is—

1. The combination of the main shaft, a speed-wheel P' thereon, the shaft K, having thereon the loosely-mounted speed-wheel P and cam J, the belt *p*, connecting the speed-wheel on the main shaft with the speed-wheel on the shaft K, and the clutch R, movable on the shaft K and adapted to engage with the hub of the speed-wheel P, whereby the shaft K and the cam J thereon are caused to revolve, substantially as described. 50

2. The combination of the main shaft, the speed-wheel P' thereon, the shaft K, having cam J and loosely-mounted speed-wheel P, the clutch R, movable on shaft K, gear *s*, meshing with the gear S on spindle *t*, gear *s'*, on the other end of said spindle, gearing with gear S', attached to the cam, whereby a slow motion is transmitted to said cam, substantially as described. 60

3. The combination of the main shaft A, provided with fast pulley I and speed-wheel P', the counter-shaft B, having loose pulleys D F and intermediate fast pulley E, the open belt G and crossed belt H, for alternately connecting the fast pulleys E and I, the shaft K, having mounted thereon a cam J, gears S' *s*, loose speed-wheel P, and clutch R, the belt *p*, connecting the speed-wheels P P', the spindle *t*, having gears S' *s'*, and the slides *n* and *o*, 70 engaged with the cam J and with the belts G and H, respectively, substantially as described. 75

In testimony whereof I have hereunto set my hand and seal in the presence of two subscribing witnesses.

HAMILTON E. SMITH. [L. S.]
